UNITED STATES PATENT OFFICE

WILLIAM R. HEWITT, OF NEW YORK, N. Y.

RAILWAY DRAFT GEAR

Application filed September 3, 1929. Serial No. 390,109.

This invention relates to draft gear for railroad cars.

It is the principal object of the present invention to provide an improved draft gear for railroad cars which will absorb and cushion heavy endwise shocks created both by impact and by a sudden pull exerted on the coupler.

In carrying out the invention, I provide a coupler connected to the frame of the car for limited endwise movement. Opposite sets of leaf springs are provided which yieldingly resist endwise movement of the coupler in either direction so as to absorb any shocks incident to impact when cars are coupled due to sudden pulls of the locomotive.

One form which the invention may assume is exemplified in the following description and illustrated by way of example in the accompanying drawings, in which:

Fig. 1 is a plan section of a draft gear embodying the preferred form of my invention, with parts broken away to more clearly disclose certain features of construction.

Fig. 2 is a side elevation of the draft gear.

Fig. 3 is a transverse sectional view through the draft gear taken on line III—III of Fig. 2.

Fig. 4 is a fragmentary view in plan section through the draft gear showing the springs in the upper chamber placed under tension by a pull exerted on the coupler.

Fig. 5 is a similar view showing the springs placed under tension by thrust imposed on the coupler.

Referring more particularly to the accompanying drawings, 10 indicates a box-like structure which forms an extension of two channel iron stringers under a car of conventional design and which form the backbone of the car floor. The structure 10 may be separate, as shown, or may be composed of the ends of the channel iron stringers cooperating to form a rectangular housing. The draft gear of the car is connected to these stringers. The draft gear includes what I prefer to term a socket member 11 which is reciprocably mounted between the channel irons or within the structure 10, as illustrated. This socket member 11 is formed

with a semi-spherical socket 12 which receives the semi-spherical end 14 of a coupler 15. This coupler extends inwardly between the stringers 10 and into the hollow socket member 11 with its end 14 engaging the 55 socket 12.

A key or connecting pin 16 extends transversely through the coupler 15 and its ends project through longitudinal slots 17 formed in the webs of the stringers 10. The pin 16 60 also extends through the socket member 11 so that the coupler 15 and the socket 11 will move axially in unison. The slots 17 permit longitudinal movement of the pin 16 and, consequently, of the socket member 11. 65

At the inner end of the socket member 11, it is formed with an upper chamber 18 and lower chamber 19 which are separated by a partition 20. The upper chamber 18 receives a plurality of nested, bowed leaf springs 21 70 and the chamber 19 receives a similar set of springs with the exception that the two sets of springs are oppositely bowed.

At the extreme inner end of the socket member 11 it is formed with a piston or 75 plunger 22 which is adapted to engage a cylinder 23. The piston 22 and the cylinder 23 constitute a dash pot for the purpose of retarding inward movement of the socket member 11 under certain conditions, as will be 80 hereinafter set forth.

Arranged at one side of the upper chamber 18 is a wedge plate 24 having a wedge 25 projecting therefrom. This wedge 25 has oppositely inclined faces and is adapted to 85 co-operate with a wedge socket 26 having faces agreeing with the faces of the wedge. At the opposite side of the lower chamber 19, I provide a wedge plate 27 which is identical with the wedge plate 24. A wedge socket 28 90 is also provided for the chamber 19 and co-operates with the wedge 29 on the wedge plate 27. From this, it will be obvious that the springs in each chamber 18 and 19 are provided with a separate wedge plate and wedge, which wedge plates bear against the springs so that longitudinal movement of the socket member 11 relative to the stringers 10 95 will cause compression of the sets of springs in the chambers 18 and 19. The springs in 100

the chamber 18 will, of course, be compressed in a direction opposite to the direction in which the springs in the chamber 19 will be compressed, as the springs are oppositely disposed and are provided with oppositely arranged wedge means.

In operation of the device, a sudden pull exerted on the coupler 15 will result in forward movement of the socket member 11 and 10 the inclined faces of the wedges 25 and 29 will ride on the inclined faces of the stationary wedge sockets 26 and 28 and will move the wedge plates 27 and 24 inwardly toward each other and result in compressing 15 the sets of springs in the chambers 18 and 19. The forward movement of the socket member 11 is limited by engagement with stop members 35 secured to the channels or stringers 10. Thus, the forward movement 20 of the coupler 15 will be yieldingly resisted by the sets of springs in the chambers 18 and 19, so as to absorb any shock and prevent the same from being imparted to the stringers 10 and, consequently, to the car.

25 In the event that a sudden end thrust is imposed on the coupler 15, the wedge surfaces on the stationary wedge sockets 26 will cause the wedge plates 24 and 27 to move inwardly and place the springs in the chambers 18 and 19 under tension and absorb the shock. A portion of the shock will be absorbed by the air cushion between the piston 22 and the inner end of the cylinder 23.

When a pull is exerted upon the coupler 15 30 and released, the springs, of course, will tend to return the coupler to its original position. The movement rearwardly of the socket member 11 is, of course, limited by the member 36 fastened to the stringers 10 and in 40 which the cylinder 23 is formed.

From the foregoing it is obvious that I have provided means for cushioning any 45 shocks imparted to the coupler in either direction and, while I have disclosed the preferred form of my invention, I wish it understood that various changes in its construction may be made by those skilled in the art without departing from the spirit of the invention as defined in the appended claims.

50 Having thus described my invention, what I claim and desire to secure by Letters Patent is—

1. A railway draft gear comprising a pair 55 of channel irons, a socket member reciprocally mounted therebetween, oppositely disposed sets of leaf springs carried by said socket member, a plate cooperating with each of said sets of springs and reciprocable transversely of said socket member, and a wedge 60 carried by each of said plates and extending through openings formed in said channel irons whereby longitudinal motion of said socket member will cause engagement between said wedges and the edges of said 65 openings and cause said plates to move trans-

versely to compress said springs, whereby the longitudinal motion of said socket member will be resiliently opposed.

2. In a draft gear of the character described, a housing, a socket member reciprocable therein, resilient means resisting reciprocation of said socket member, a stop member limiting movement of the socket in one direction and having a cylinder formed therein, and a piston carried by the socket 75 and positioned to enter said cylinder upon movement of the socket toward the stop member.

3. In a draft gear of the character described, a housing having openings formed 80 in opposite sides thereof, a socket mounted for reciprocation in said housing, resilient means carried by the socket, plates engaging said resilient means and wedges carried by the plates and extending through said openings whereby reciprocation of said socket will cause the wedges to engage the edges of the 85 openings and effect a compression of the resilient means.
